UNITED STATES PATENT OFFICE.

GEORGES HENRI RIBICHON, OF THREE RIVERS, QUEBEC, CANADA.

PULL-OVER GARMENT.

Application filed January 17, 1927. Serial No. 161,650.

This invention relates to improvements in pull over garments and the object of the invention is to provide a pull over garment, particularly adaptable for children, so as to give warm protection to the breast and back of the child without interfering with the good circulation of the blood at the waist line, not permitting snow entering the pull over garment at the same point when the child plays in the snow while being at the same time a protection to the other garments worn by the child, preventing the garment from bagging and giving a better appearance as a whole to the garment fitted upon the child.

A further object is to provide a garment of this character which can be conveniently and easily placed upon the wearer.

A further object is to provide a garment of this description that will be simple and economical to manufacture and which will provide complete protection for the wearer.

A still further object is the provision of a garment without sleeves that can be secured and removed from the wearer quickly.

With these and other objects in view the invention consists of a pull over garment formed from knitting fabric or other suitable material comprising a body portion open at the top and having leg portions integral therewith, no special apertures being necessarily provided for the arms and for the head or neck, and provided with suitable means at the top adapted when engaged to cause the garment to fit snugly around the arms and neck of the wearer.

Referring now to the drawings in which like characters of reference indicate corresponding parts in each figure:

Figure 1 is a front elevation of my improved pull over garment detached,

Figure 2 is a similar view of the garment fitted on a child,

Figure 3 is a side view of Figure 2,

Figure 4 is a fragmentary front view with the arm uplifted,

Figure 5 is a fragmentary front view of a modified form.

Referring more particularly to the drawings, in which a preferred example of my invention is disclosed A indicates the garment as a whole formed from knitting fabric or other suitable material providing leg portions 10 and 11 and body portion 12, the latter being opened at the top as at 13 and provided on opposite sides of the open top with

fastening members, such as buttons 14 and 15 and buttonholes 16 and 17 adapted in engagement as illustrated in Figure 2 to bring the top of the garment together to form the neck and armholes 18 and 19 whereby the garment fits snugly on the wearer and whereby it is easily and quickly put on or taken off.

It will be noted that no provision is necessarily made in the sides of the body portion for armholes nor is there any provision necessarily made for a neck portion, thereby simplifying the construction and permitting the garment to be manufactured at very low cost. In short the combination with the open top and fastening means therein in operation provides armholes and a neck opening by drawing the top at spaced predetermined points together in a detachable connection.

If anybody would prefer there is some kind of aperture at the neck or at the arms, or at both neck and arms, so as to relieve any crumpling when joined together, this of course could be done without departing from the spirit of the device. Furthermore the fastening means may be buttons, snaps, cords, ribbons, or any other suitable device, one or more of which may be used with either single or overlapping edges either one way or another at the top. The top edge as well as any other portion of the garment may also be reinforced if found advisable. One may find preferable to add to this new device a string at some part of the portion body, so as to use the new garment in both ways, that is above or below the shoulders, and by so doing it is understood it will not depart from the spirit of the new discovery.

From the foregoing the operation of wearing the garment will be apparent. It is simply slipped on over the body of the wearer and the fastening means in the top brought together and engaged. To remove the garment it is only necessary to disengage the fastening means in the top and pull it off.

In the modified form as illustrated in Figure 5 the garment is provided with fastening means such as double buttons 14^a and 15^a and button holes 16^a and 17^a which when fastened provide a more restricted opening of both the neck and arm holes.

As many changes could be made in the above construction and many apparently widely different embodiments of my invention within the scope of the claim constructed without departing from the spirit or scope thereof, it is intended that all matter con-

tained in the accompanying specification and drawings shall be interpreted as illustrative and not in a limiting sense.

What I claim as my invention is:

- 5 A unitary step-in garment of stretchable material having an upper body portion, a lower body portion, and leg and foot portions, all of the said portions being integral and continuous with each other, the top of
- 10 said garment being provided with a body opening extending across the top of the gar-

ment with the rest of the garment being closed and unopened, and separable fastening means arranged adjacent the said body opening to enable the top of said garment to be secured over the shoulders of the wearer in such a manner as to fit snugly around the neck and arms. 15

In witness whereof I have hereunto set my hand.

GEORGES HENRI ROBICHON.
